UNITED STATES PATENT OFFICE.

HERBERT HENRY BERRY AND JAMES WATT REID, OF LONDON, ENGLAND.

HEATING ELEMENT FOR ELECTRIC FIRES, RADIATORS, AND THE LIKE.

Application filed April 5, 1926, Serial No. 100,004, and in Great Britain April 6, 1925.

This invention relates to heating elements for electric fires or radiators and of the kind comprising a rod or bar of insulating material having both longitudinal grooves and 5 spiral or helical grooves of the two start or double thread type and into each of which a coiled resistance wire is placed, said wires being so connected to the source of electrical supply that one wire can be used alone or 10 both can be simultaneously used.

According to our invention the rod or bar is tubular and the resistance wires are at one end connected to separate metal side plates insulated from each other and having means 15 for the connection of leads; the said side plates being held in position on the said bar or rod by a block of insulating material which is secured by a nut on a bolt which passes completely through the bar to the 20 other end. The said block may advantageously provide means for holding the element in clips carried by the fire or radiator, in which case the leads are sufficiently long to permit their electrical connection to contacts in the fire or radiator positioned as 25 remotely as possible from the element.

An example of the invention is shown in the accompanying drawings, in which:

Fig. 1 shows one of the elements having a 30 double winding and three flexible leads.

Fig. 2 is an end view of the same element but on a larger scale and with end block 11 removed.

In Fig. 1 the element is seen from the back 35 or underneath as indicated by the arrow 1 in Fig. 2. This element comprises a bar or rod *a* of insulating material which forms a support for the resistance wires 1 and 2. The said support has ribs 3 in which are recesses 4 arranged in double helical manner 40 for the two wires. The wire 1 is connected at 5 to a side plate 6 and the wire 2 is connected at 7 to a side plate 8, these plates are insulated from each other so that the wires 45 1 and 2 are isolated at that end but they have a connection in common at 9 on the ring-plate 10. The support is extended by blocks 11 and 12 which provide means for supporting the whole element as by placing the said 50 blocks in the usual spring clips or brackets.

A rod 13 extends throughout the element and is fitted with end nuts 14 by which the parts can be easily held together to form a cartridge. The support *a* is also grooved 55 longitudinally at 15.

Flexible, insulated leads 16, 17 and 18 are connected respectively at 5, 7 and 9 to the wires. The leads 16 and 17 have plug terminals 19 and 20 and the lead 18 has a blade terminal 21. These terminals coact with 60 contacts, not shown, but which may be of any suitable known or convenient kind.

It will be seen that the edges 22 and 23 of the plates 6 and 8 are bent over into grooves in the support; this is for the purpose of 65 preventing turning movement of the plates on the support.

The flexible leads 16 and 17 are shown as 70 separate members but they may be of twin form with a suitable contact.

If a small amount only of heat is required one only of the wires 1 or 2 is employed but because it extends over the full heating length of the element, the said full length becomes radiant as differing from a section 75 only of the element which is the method hitherto adopted when two separately-usable wires are employed and to use the full length in this way makes the fire or radiator more attractive than one in which one half of the 80 element is not heated and is therefore dull.

When full heat is required both wires are put into use.

What we claim is:

1. A heating element for an electric fire or 85 radiator comprising a tubular central bar grooved longitudinally and/or with two start helical grooves, separate resistance wires in the helical grooves, separate metal plates, one for each wire at one end of the bar, a 90 block of insulating material for holding the metal plates to the bar and a bolt having a nut and passing completely through the bar and the block for holding the block to the bar.

2. A heating element for an electric radiator comprising a bar of insulating material which has two spiral grooves and also longitudinal grooves, a resistance wire in each spiral groove, a metal plate for each wire at 100 one end of the bar, bent portions on the plates to engage the longitudinal grooves, a block of insulating material at the end of the bar for holding the said plates thereon and a bolt passed through the bar to hold the 105 block in place at the end thereof.

In testimony whereof we affix our signatures.

HERBERT H. BERRY.
JAMES WATT REID.
